LIQUID DISPENSING DEVICE

Cecil W. Smith, Waterman, Ill.

Application May 15, 1936, Serial No. 79,834

7 Claims. (Cl. 120—69)

This invention relates to ink containers, and in its illustrated form includes a main container, with a removable top having a recess therein and an inner container or well supported within the neck of the main container in such manner that it may be filled from the main container by tipping the main container upside down to let the ink run into the top, and then uprighting it to let the ink run from the top into the inner well.

Ink containers of this general type have been known heretofore, and in fact this invention may be considered an improvement on that disclosed in my Patent No. 2,055,509, issued September 29, 1936, on an application filed October 22, 1934, and copending with this application. However, it also covers certain features disclosed but not claimed in said patent, and to that extent it is a continuation in part of said application.

One of the features of this invention consists in shaping the inner well in such manner as to support a wide variety of fountain pens in the proper position for filling without letting the point of the pen touch the bottom of the well, or without interfering with the filling operation, thus avoiding the possibility of injury to the point. It should be noted that this feature can be incorporated in almost any type of inkwell.

Another feature of the present invention is the provision of a bottle neck and removable top construction in which leaking and dribbling are effectively prevented, and in which certain other unsatisfactory conditions of prior ink containers have been eliminated. For example, the washer which prevents leaking is now secured in the container in such a way that it is practically impossible for it to come loose any time during the life of the container. This is accomplished by the aid of fine grooves and anchoring projections on the inside of the top into which the washer is pressed. These grooves and fins have been so shaped that they do not add to the manufacturing difficulties.

The combination of a bottle neck, the top of which is substantially flat except for a slight inward slant together with a fairly thick and somewhat plastic washer, has substantially eliminated the danger of small amounts of ink running onto the outside of the bottle as the top is removed. As a matter of fact, the flat top of the neck will usually be left completely clean, but even if, with frequently repeated use, the ink gradually works onto this top surface, it will tend to flow from this surface back into the bottle instead of dribbling over to the outside of the bottle.

It is therefore an object of the present invention to provide an ink well of the type described which properly supports all or nearly all types of pens for filling without injuring its point, and which provides an adequate supply of ink within the auxiliary well for filling the pen.

A further object of the invention is to provide an ink container having an inner well therein and having a closure construction of such nature that the container is dependably sealed against leakage, and the presence of small amounts of ink on the outside of the bottle is prevented.

Another object is to provide a cap having its threads so formed that the cap will fit bottles which are imperfectly formed. This is accomplished by making the cap threads thinner and shaped with substantially horizontal upper faces.

Other objects and advantages of my invention will be apparent from the following description, taken with the drawing, in which:

Fig. 1 is a vertical sectional view through the preferred form of this invention, showing the bottle cap removed and a pen in place for filling.

Fig. 2 is a view somewhat similar to Fig. 1 but on a larger scale and showing the outside of the inner well and showing the cap in place.

Fig. 3 is a fragmentary sectional view of the cap on a still larger scale, in fact, approximately four times actual size, with the washer removed.

Fig. 4 is a developed view of the threaded portion of the bottle cap; and

Fig. 5 is a sectional view through the cap substantially along the line 5—5 of Fig. 3, with the washer removed.

Although this invention may take various forms, only one has been chosen for illustration. In this form the invention includes a bottle 11, normally sealed by a cap 12 and having an inner well 13 supported in its neck by ribs 14, the construction being such that the inner well 13 may be filled by tipping the bottle upside down and then quickly uprighting it.

The outside of the inner well 13 is preferably substantially the same as that shown in applicant's copending application Serial No. 749,423, except for slight changes resulting from internal improvements, and therefore may be discussed quite briefly. The inner well is approximately of cone shape, and at its upper or larger end is provided with a plurality of ribs 14, preferably an odd number thereof, to provide the greatest degree of resilience and to avoid the rocking effect that might be obtained with diametrically opposed ribs. Each of the ribs 14 is provided with a longitudinally extending V-shaped groove 16 to provide two longitudinally extending thin edges

17 as seen best in Fig. 2. These thin edges may be called feather edges since they will yield to the extent necessary to fit into the neck of the bottle while at the same time clinging tightly to the 5 neck so as to retain the proper position once it has been inserted.

It is desirable that that part of the outer wall of the inner well between the ribs 14 be so shaped as to facilitate the flow of ink from the 10 bottle into the cap without enabling it to flow too easily in the reverse direction. To this end the top of the well extends quite close to the neck of the bottle, but recedes therefrom downwardly. Since considerable radial pressure may be exerted 15 on the inner well by the bottle neck, it is desirable to have a strong annular thickened portion 21 as seen in both Figs. 1 and 2, adjacent to the ribs.

The preferred form of the inside of the well is 20 that shown in Fig. 1, in which near the bottom there is an annular shoulder 23 so positioned and of such diameter that the sides of the pen will rest thereon as seen in Fig. 1, without permitting the pen point to touch the bottom of the well.

25 With the prevalence of the plunger type of pens, protection of the pen point has become more necessary than heretofore because of the downward pressure exerted on the pen in operating the plunger. The shoulders 23 protect 30 the pen point adequately while at the same time having no adverse effect on the filling of the pen. Because the shoulder 23 provides a circular opening and because the corresponding portion of 35 the pen is not circular, there is sure to be a passage for flow of the ink between the upper end of the well and the lower end of the well. The level of the ink is sufficiently high to provide an adequate supply of ink for one filling before the ink drops too low to be drawn in. Of course the 40 inner well may also be made of a larger diameter if the bottle neck is larger in diameter.

The form shown in Fig. 1 is especially satisfactory for the reason that it will properly support all or nearly all pens, for although the pens 45 vary considerably in the diameter of the barrels, there is relatively little variation in the tapers of the lower portions of the pen points, and with the illustrated structure, the position of the pen is determined entirely by the taper of the 50 point.

In an ink container or bottle including an inner well such as the well 13, it is extremely important to have a good seal for the bottle, because of the necessity of turning the bottle upside down to 55 fill the inner well. As a matter of fact, in some proposed bottles having an inner well, in the past, the worst feature has been the unsatisfactory sealing of the cap. The difficulty lies not only in providing a cap which will be leak-proof, while firmly screwed down, but in providing 60 a cap which may in fact be screwed down firmly irrespective of irregularities in the thread portion of the liquid container which often causes binding of the cap on the bottle, so as to make 65 screwing of the cap difficult, or binding so great as to make removal of the cap substantially impossible. There is a difficulty in providing a cap which will not permit small amounts of the ink to dribble down on the outside of the bottle as 70 the cap is removed, and furthermore, providing a cap in which the sealing means such as the washer will stay in place permanently. The present invention presents a very satisfactory solution of all these difficulties.

75 It will be noted that the top of the bottle neck

is provided with a nearly flat annular surface 31 which has a very slight inward slope. The very tip 32 of the bottle is approximately at the outside edge of the neck. This bottle construction may not be new in itself, but in combination with applicant's sealing means the result is very much better than has been attained heretofore. 5

The sealing means includes a washer 33 which may desirably be any paper product such as 10 chip board treated with a plastic waterproof material such as paraffin. A mixture of 75% paraffin and 25% beeswax is preferred and has the advantage of greater adhesive qualities than paraffin alone. The adhesiveness helps to hold 15 the washer in place. The washer is preferably fairly thick so that it will yield enough to seal against the entire top surface 31. The result is that ink will not ordinarily get onto said surface at all, since when the bottle is upside down, 20 the cap 12 is screwed tightly onto the bottle, and the washer 33 is therefore in firm contact with the entire surface 31. When the bottle is uprighted, substantially all of the ink flows off of the cap. In this connection it should be noted 25 that there is no downwardly projecting part on the inside of the cap on which small amounts of ink would be particularly likely to hang. Of course it is inevitable that very tiny amounts of ink may occasionally remain on the cap. In the 30 course of many uses this ink may gradually spread onto the washer 33 and be transferred by it to the surface 31, but since this surface slants inwardly, it is virtually inconceivable with normal use that ink will ever get beyond the tip 35 32 and dribble onto the outside of the bottle.

One of the major difficulties with a cap of this type is the retention of the washer 33 in the cap. Of course when it is not retained, a leaky cap 40 is likely to result, and even at best the user is likely to get his fingers dirty in putting the washer in place.

According to the present invention, the washer 33 is retained in place by three expedients. First, 45 an annular depending flange 36 is provided. This not only provides another surface for increasing the friction by which the washer 33 is held in place, but also positively prevents spreading of the washer, and thereby insures its effectiveness and prevents it from catching ink as the 50 bottle is uprighted. In addition to this, the seat for the washer is provided with a plurality of fine annular grooves 38. Even the combination of the flange 36 and the grooves 38 would not be dependably effective alone and therefore projections 39 have been provided. The provision of such projections presented a difficulty because of the necessity of unscrewing the cap from the die after the molding. This difficulty has been solved, however, partly by making the projections 39 in the form of threads having the same 55 pitch as the main thread 41, by which the cap is secured to the bottle. This is best seen in Fig. 4, in which this portion of the cap has been developed and the anchor threads 39 are seen 60 as being parallel to the main thread 41. Also, the anchor threads 39 must be so positioned that the die forming them will pass out between the threads 41. To this end the anchor threads 39 65 are formed as projections on an annular shoulder 43 which has a radius no greater than the smallest radius of the thread 41, and preferably slightly less than the radius of thread 41 to permit easy 70 insertion of the washer 33 past the screw threads 75

to be pressed into place at the anchor threads 39 as will be hereinafter explained.

In assembling the wax treated washer 33 in the cap 12, it is dropped into the open end to preferably fall down as far as the threads 39 where it is pressed in with enough pressure to cause the wax and the fibers of the paper itself to expand into the grooves 38 and in between the threads 39, thus securing the washer 33 in place so permanently that it cannot even be picked out with a knife except in small bits. The washer may be slightly oversize with respect to the thread portion 39 so that it will snap into place, and the pressure may be such as to cause the wax to melt and flow. To increase this latter effect the washer may be heated if desired.

In order that the anchor threads 39 may have the greatest possible retaining effect on the washer, they are preferably shaped in cross section as shown best in Fig. 3 with their upper sides approximately horizontal. The portion of the thread below the horizontal face, as viewed in Fig. 3, is inclined to facilitate the sliding of the washer into place to be retained by the cooperation of the thread construction as discussed.

One very difficult problem in connection with ink containers of this general type was to find a material suitable for the caps and inner wells which could be molded quite accurately to the required shapes, and which would withstand long contact with the ink without discoloring the ink, and without being corroded by the ink. After extensive search it was found that the molded phenolic resin known and available commercially as "Durez" was ideal for this purpose, being so inert that all of the ordinary inks can stand in the well for months or even years without any noticeable deleterious effect.

In the past many bottles have had to be discarded because of imperfections in the bottle threads and neck causing binding or sticking of the caps on the bottle, which either prevented proper screwing of the caps, or caused breakage of the caps. According to the present invention this difficulty has been largely overcome by changing the main thread formation of the cap to that shown in Figs. 2 and 3. The thread 41 is smaller in a vertical direction than the intended size of the groove 48 between threads 46 on the bottle, and the space 47 between convolutions of thread 41 is larger than the intended size of thread 46 both in radius and in the vertical direction. This is largely accomplished by forming the threads 41 approximately horizontal on their top surface.

The bottle thread is normally rounded, with the portion immediately adjacent the neck of the bottle substantially horizontal. This portion may be extremely small, and it is simply the standard construction for glass bottle threads. With a corresponding rounded surface on the cap thread, as has been used in the prior art caps, there has been a wedging force developed between the cap and bottle due to manufacturing irregularities in the threads of an inexpensive glass bottle, causing the difficulty mentioned above. With the upper horizontal surface construction for thread 41 as shown in Figs. 2 and 3, there is a straight surface on the cap thread in engagement with the surface of the bottle thread, and the lip 42 will ordinarily bear against the inside substantially horizontal portion of the bottle thread to provide a horizontal surface engagement between the two.

Of course the cap securing force is still exerted

on the threads 41 in a downward direction, but the wedging force due to a rounded cap thread surface on radially oversize bottle threads or on vertically oversize bottle threads, is eliminated unless the imperfections of the bottle are entirely out of reason. Furthermore, should there be any slight accumulation of liquid or other matter on the bottle thread, it has been found that the front lip 42 cuts through this better than a rounded thread would. In other words, it makes the cap threads capable of fitting bottles easily in spite of relatively large variation in the bottles, and provides for a smooth action of the cap on the bottle.

From the foregoing it is seen that an ink container is provided which not only furnishes a convenient means for filling fountain pens or dipping ordinary pens without injury to the points, but also can be used for months or years with complete satisfaction both in preventing evaporation to maintain the quality of the ink, and in avoiding dribbling of the ink to the outside container or dropping of the washer from the container cap. It is understood of course that the well and cap may be used with a container for any liquid.

Although only a few embodiments of my invention have been herein shown and described, it will be understood that I am not limited thereby, but limit my invention only by the scope of the appended claims.

I claim:

1. An ink well including a body member having a cavity therein closed at the bottom thereof and having imperforate side walls, a lower portion of which cavity is of reduced cross section to form an annular shoulder for engaging the pen point nibs of a pen inserted into said well and holding said pen with its point out of contact with said well but close to the bottom thereof, and with the holder below the normal level of ink in the well; the cross sectional shape of said shoulder formed by the reduced portion being different from that of the nib portion of a pen which it is designed to engage, to prevent sealing of the lower part of said well; the interior of said well being free from horizontal surfaces and from upstanding members above the closed bottom of the cavity, whereby possibility of the pen point being caught as it is inserted vertically into said well is eliminated.

2. The combination of an ink container having a neck opening, a one-piece cap closing said opening and having a cavity in the roof thereof, a well in said neck adapted to be filled by inverting said closed container and uprigting it, a washer secured in said cap, and sealed against the top of said neck opening; said cap having a downwardly extending annular flange, having main threads thereon for securing the cap to said container, an annular vertical wall extending above said flange and having fine anchor threads thereon above said main threads for securing said washer in place, said anchor threads being of the same pitch as said main threads, and being so positioned that the die member forming them and the main threads may be unscrewed from the cap.

3. The combination of an ink container having a neck opening, a one-piece cap closing said opening and having a cavity in the roof thereof, a well in said neck adapted to be filled by inverting said closed container and uprigting it, a washer secured in said cap, and sealed against the top of said neck opening; said cap having a down-

75 70 75

- wardly extending annular flange, having main threads thereon for securing the cap to said container, and having fine anchor threads in an annular vertical wall above said main threads for securing said washer in place, said anchor threads being of the same pitch as said main threads, and being so positioned that the die member forming them and the main threads may be unscrewed from the cap, and the upper sides of said main threads being approximately horizontal to form a relatively sharp edge for cutting through any foreign substances on the container neck for easy removability of said cap from said container.
4. The combination of an ink container having a neck opening, a one-piece cap closing said opening and having a cavity in the roof thereof, a well in said neck adapted to be filled by inverting said closed container and uprighting it, and a washer secured to said cap and sealed against the top of said neck opening; said cap having a downwardly extending annular flange having main screw threads thereon for engaging threads on said container, and having similarly disposed fine anchor threads above said main threads in said cap for securing said washer in place, a seat above and adjacent said anchor threads, and a depending flange on the opposite side of said seat from said threads to form a cavity for the washer, and a washer pressed into said cavity and intimately engaging said anchor threads.
5. The combination of an ink container having a neck, an inner-well therefor for filling a fountain pen therein, said inner-well being open at the top and closed at the bottom, means for supporting said well in said neck and spacing said well from said neck at intervals around the same to provide openings from the container extending past said well for the flow of ink therethrough, a removable cap for closing said neck and having a cavity therein for receiving ink when the bottle is inverted and pouring said ink into said well when said container is uprighted, said well having imperforate side walls with a continuous annular shoulder therewithin intermediate the top and bottom thereof positioned to engage a pen point of a fountain pen at the nibs portion

thereof and support said pen out of contact with the bottom of the well for filling said pen with ink poured into said well from said cap.

6. The combination of a liquid container having a neck opening, a one-piece cap closing said opening having a cavity in the roof thereof, securing threads on the inner wall of said cap at the lower portion thereof, a washer in said cap and sealed against the top of said neck opening, and means for retaining said washer on said cap and preventing the spreading of said washer, said means comprising an annular seat in said cap cavity, a plurality of annular concentric grooves in said washer seat having the washer material therein, an annular flange on one side of said seat and the inner wall of the cap on the other side thereof, a plurality of fine anchor threads on said inner wall adjacent said seat above said securing threads having the washer material pressed therein, with said securing threads and anchor threads of said cap being of the same pitch for easy removal of the cap from the apparatus for making said cap in an unscrewing movement.

7. An ink container having an open neck with the usual rounded cap securing threads on the outside of said neck, a cap for said container having a cavity therein, an inner well closed at the bottom and open at the top supported in said neck in a manner to provide an ink passageway from the bottom of said container past said inner well to said cavity for the flow of ink thereto when said container is inverted, said cap acting to pour said ink into said well when the container is uprighted, a washer secured in said cap for engagement with the top of the open neck to normally seal said cap and container during the turning operation, and said cap having a securing thread thereon with its upper side approximately horizontal to form a sharp corner along the inner edge thereof to engage the rounded container thread with said sharp corner for cutting through ink accumulated on said rounded thread and make for easy threaded movement of said cap on said container.

CECIL W. SMITH.
